SIDE FRAME FOR RAILWAY CAR TRUCKS

Harry W. Stertzbach, Columbus, Ohio, assignor to
The Buckeye Steel Castings Company, Colum-
bus, Ohio

Application November 29, 1943, Serial No. 512,191

6 Claims. (Cl. 105—206)

1

This invention relates to railway car trucks and more particularly to cast metal side frames for such trucks.

An object of the invention is to provide a novel construction whereby the stresses will be more evenly distributed than in the side frames heretofore known, and deformations of the journal box or breakage of the members of the frame will be eliminated.

With the foregoing object outlined and with other objects in view, which will appear as the description proceeds, the invention consists in the novel features hereinafter described in detail, illustrated in the accompanying drawings, and more particularly pointed out in the appended claims.

In the drawings:

Fig. 1 is a side elevation of one-half of a side frame, including my improvements, it being understood that the other half is identical in construction with the half illustrated.

Fig. 2 is a bottom plan view of the same.

Fig. 3 is a fragmentary transverse vertical sectional view taken on the line 3—3, of Fig. 2.

Figs. 4 and 5 are sectional views, respectively, taken on the lines 4—4, and 5—5, of Fig. 1.

Fig. 6 is a top plan view of the journal box portion of the side frame.

Fig. 7 is a fragmentary vertical sectional view on the line 7, 7, of Fig. 6.

Fig. 8 is a fragmentary side elevation of a modification.

In accordance with the present invention, the diagonal compression member 9 and the diagonal tension member 10 are both of inverted channel form. The inclined top plate or web 11 of the tension member gradually increases in thickness toward and merges with the top plate 12 (Fig. 7) of the integral journal box 13, where the top plate of the box joins the side wall 14 of the inner lug of the box and forms a continuous connection between this point and the top plate 15 (Fig. 1) of the spring seat member 16. For strengthening purposes, it is advantageous to have the web of the diagonal tension member join the top of the journal box at the point where the wall of the inner brass lug also joins the top of the box.

As the side frame is of cast metal, my construction contemplates the use of symmetrical cores (not shown) inside of the box during casting, the beveled corners 17 (Figs. 6 and 7) being used at both the inner and outer corners of the box, with the width of the beveled cores being equal to the outside width of the diagonal ten-

2

sion member where it joins the journal box. At this point, it will be noted in Fig. 7, that the side wall 14 of the inner lug of the journal box is spaced from the inner wall 18 of the box.

5 The spring seat member, in accordance with my invention, is formed in hollow box section, as shown in Fig. 3, with the top plate 15 wider than the box section portion, and provided with marginal upstanding inner and outer flanges 19 and 20 for retaining the springs, not shown.

An alternative means for joining the bottoms of the diagonal tension members and the spring seat member is illustrated in Fig. 8, in which the bottom 21 of each tension member forms an ogee 15 curve, being shaped convex downwardly under each of the bolster columns 22 and changing to concave downwardly in a direction toward the journal box or the end of the frame. Such constructions strengthen the connection between 20 the diagonal tension members and the spring seat member.

The columns 22 have parti-cylindrical surfaces 23, interrupted by medial vertical guide flanges 24, adapted to cooperate with correspondingly 25 shaped surfaces on the bolster, not shown.

The upper portion of the bolster opening 25 is widened for a distance A below the top 26 of the frame to permit the passage of bolster lugs, not shown.

30 From the foregoing, it is believed that the details of my improved side frame and the constructional advantages thereof will be readily understood by those skilled in the art, and it will be apparent that changes may be made in the 35 side frames illustrated without departing from the spirit of the invention, as expressed in the following claims:

What is claimed and desired to be secured by Letters Patent is:

40 1. A railway car truck side frame comprising diagonal compression and tension members converging toward an end of the side frame, a journal box integral with the outer ends of said members and having a substantially flat horizontal top, said journal box having inner and outer internal lugs provided with side walls spaced from the side walls of the journal box, the tension member having an inclined top web which terminates at and merges with the top of 50 the journal box at the place where the upper end of the wall of the inner lug merges with the top of the box, said web gradually increasing in thickness toward the top of the journal box, the top of the journal box having internal beveled 55 surfaces arranged at opposite sides of the lugs

and spaced from the front and rear ends of the journal box, the beveled surfaces terminating substantially at the inner surfaces of the lugs, and the beveled surfaces adjacent the inner lug being in substantially the same plane as the bottom surface of the web of said tension member.

2. A railway car truck side frame comprising compression and tension members, each of inverted channel shape, said members converging toward an end of the frame, a journal box arranged at said end of the frame and integral with said members, said box having a top and the tension member having a top web merging with said top, the bottom of the top having four symmetrically placed beveled inner surfaces spaced from the front and rear ends of the journal box, each pair of which transversely of the frame is spaced a distance equal to the width of the tension member.

3. In a railway car truck side frame, integral tension compression and journal box members, the tension members having a top web merging with the top of the journal box member, the journal box member having a substantially horizontal top and inner and outer lugs provided with side walls merging at their upper ends with the top of the journal box member, said top of the journal box member having internal beveled surfaces arranged at opposite sides of the lugs and spaced from the front and rear ends of the journal box.

4. In a railway car truck side frame, integral tension compression and journal box members, the tension member having a top web merging with the top of the journal box member, the journal box member having inner and outer lugs provided with side walls merging at their upper ends with the top of the journal box member, said top of the journal box member having internal beveled surfaces arranged at opposite sides of the lugs and spaced from the front and rear ends of the journal box, and the beveled surfaces adjacent the inner end of the lugs being in substantially the same plane as the bottom surface of the web of said tension member.

5. A railway car truck side frame comprising integral compression, tension, and journal box members, said compression and tension members converging toward the journal box, and the compression member having a top web, said journal box member being provided with inner and outer substantially vertical lugs which are substantially in alignment with the compression and tension members longitudinally of the frame, 10 said lugs having side walls spaced inwardly from the side walls of the journal box, the web of the tension member merging with the top of the journal box where the side wall of the inner lug merges with the top of the journal box, the top of the journal box having pairs of bottom beveled surfaces, the beveled surfaces of one pair being spaced from the front and rear ends of the journal box and arranged respectively at opposite sides of the inner lug and being in substantially the same plane as the bottom surface of the web of the tension member.

6. A railway car truck side frame comprising an integral compression member, tension member, and journal box, the compression and tension members converging toward the journal box and each being of inverted channel shape, a spring seat formed on the medial portion of the tension member, and columns connecting the tension and compression members, said tension member having an inclined top web terminating at and merging with the top of the journal box and the top of the spring seat, the top of the spring seat being wider than the remainder of the tension member and said remainder being 25 of box section, upstanding flanges provided at the edge portions of the spring seat and merging at their ends with said columns, the top of the journal box having pairs of bottom beveled surfaces, the beveled surfaces of one pair being 30 spaced from the front and rear ends of the journal box and arranged respectively at opposite sides of the tension member and being in substantially the same plane as the bottom surface of the web of the tension member.
